(57) **CLAIM**

The ornamental design for a latch, as shown and described.

DESCRIPTION

FIG. 1 is a top, front, and right perspective view of a latch showing our new design;

FIG. 2 is a top, rear, and left perspective view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a left side elevational view thereof; and,

FIG. 8 is right side elevational view thereof.

The broken lines environment is for illustrative purpose only and forms no part of the claimed design.
